UNITED STATES PATENT OFFICE.

HARLEY E. ANDERSON, OF CHICAGO, ILLINOIS, ASSIGNOR OF ONE-HALF TO WILLIAM L. KELLOGG, OF CHICAGO, ILLINOIS.

BRAKE RIGGING FOR RAILROAD CARS.

Application filed August 31, 1922. Serial No. 585,480.

To all whom it may concern:

Be it known that I, HARLEY E. ANDERSON, a citizen of the United States, residing at Chicago, in the county of Cook and State 5 of Illinois, have invented a certain new and useful Improvement in Brake Rigging for Railroad Cars, of which the following is a full, clear, concise, and exact description, reference being had to the accompanying 10 drawings, forming a part of this specification.

My invention relates to improvements in brake riggings for railroad cars.

Objects of my invention are to provide a 15 brake rigging in which the slack in the brake chain of a hand-operated brake may be quickly taken up and the brakes applied, and the power of application then quickly and effectively multiplied through the 20 operation of an interposed device which, for convenience, I call a brake booster.

Another object is to provide a high power 25 hand-operated brake mechanism. A further object is to provide a simple and efficient hand brake mechanism for railroad cars. Other objects will appear from the description 30 of the invention hereinafter following.

In the drawings forming a part of this specification, Fig. 1 is an end elevation of a railroad box car body, broken away intermediate 35 its upper and lower portion showing a form of my invention as applied to a railroad car. Fig. 2 is an enlarged central vertical longitudinal section, partly in side elevation, of the brake booster mechanism showing the parts in their normal position of full release. Fig. 3 is a vertical, longitudinal section, partly in side elevation, showing the same parts in full compression—that is, with the brakes fully applied. Fig. 4 is a cross section, taken on line 4—4 40 of Fig. 2. Fig. 5 is a cross section taken on line 5—5 of Fig. 2. Fig. 6 is a cross section taken on line 6—6 of Fig. 2. Fig. 7 is a bottom plan view of the brake booster device. Fig. 8 is a detail perspective view showing the T-headed end of the brake rod. And Fig. 9 is a side elevation of the yoke element 45 which is one of the members of the brake booster device.

Referring to the drawings, the numeral 10 indicates a freight box car body broken away as will be observed at the numeral 11, having a brake staff 12 broken away at 13

in Fig. 1 of the drawing, which brake staff 55 is of a usual design and secured to the car in the usual way, having a brake wheel 14 and a brake chain 15. A brake rod is indicated by the numeral 16, only one end being shown, the other end being designed to be 60 attached to the brake equalizer lever, not shown, but in the usual manner as will be well understood.

The brake booster mechanism embodying a form of my invention is shown on Fig. 1 65 of the drawings at 17. The particular embodiment illustrated will now be described. It consists of a housing member, preferably a casting 18, which is suitably affixed to the underside of the car floor, or the car under-frame, as may be desired, by any efficient means as, for instance, the lugs 19—19 perforated as at 20 for the passage of bolts or other appropriate securing means. The housing member 18 is, broadly speaking, of 75 an inverted trough shape, being open below and at its ends and having an upper plate 21 provided along its length with a rack 22 having downwardly projecting teeth 23. Its side plates 24—24 are each provided with a 80 longitudinally extending pin way or groove 25 and a yoke way or shoulder 26 which, in the structure illustrated in the drawings, is formed by the integral brackets 33 depending from the side plates 24 of the housing 85 member 18.

Within the housing member there is mounted a yoke 27 open at its outer end and closed at its inner end by the cross member 28 which connects its two arms 29—29. The 90 cross member is upon its inner face provided with a boss 30. As shown, it is integral with the cross member 28 of the yoke and is perforated as at 31 for the passage of the brake rod 16. The arms 29 of the yoke are 95 perforated at their forward ends as at 32—32 for the passage of the pin 34, whose ends are received in the pin ways 25 and is adapted to move longitudinally therein.

A lever 35 is mounted upon the pin 34 100 which passes through the perforation 36 therein and is provided on either side with an outwardly extended hub 37, hereinafter more particularly described. The lever arm 38 has at its outer end 39 a perforation 40, 105 by means of which the lever 35 is attached to the brake chain 15 through the interposition of the clevis 41 and the clevis pin 42 which

is passed through the perforation 20. A block 43 is mounted between the arms 29—29 of the yoke 27, having on its outer lateral faces the grooves or ways 44—44 adapted to slide 5 upon the beads 45—45 with which the inner lateral faces of the arms 29 of the yoke 27 are provided. Thus, it will be observed that the yoke 27 is supported by the housing member 18 and that the block 43 is supported 10 by the yoke 27. Near its inner end the block 43 is provided with a shoulder or spring seat 45, rearwardly of which a boss 46 extends. A spring 47 is mounted between the rear member 28 of the yoke 27 surrounding 15 the boss 30 thereof, and the spring seat 45 upon the block 43 surrounding the boss 46 thereof, over-compression of which is prevented by the engagement of the bosses 46 and 30 respectively upon the block 43 and the 20 yoke 27, as illustrated in Fig. 3 of the drawing. Thus the said bosses 30 and 46 function as limiting stops, as will be readily understood. At its outer end the block 43 is vertically bifurcated, thus providing block arms 25 48—48 between which the lever 35 is adapted to be received, which most clearly appears from an examination of Figs. 7 and 2 of the drawings. The said block arms 48—48 are each provided with outwardly opening jaws 30 49 formed between the upper jaw members 50 and the lower jaw members 51. Within these jaws, or speaking of the structure as a whole, the jaw of the block member, the hubs 37, or, described as a whole, the hub of the 35 lever 35 is adapted in normal position of the parts—that is, when the brakes are released, to be received. The lever 35 is at its hub end provided with a mutilated gear 52 comprising a plurality of teeth 53—53 which are 40 adapted in one position of the lever 35 to engage with the teeth of the rack 22, and in other positions to be disengaged therefrom and to permit the entry of the hub of the lever into the jaws 49 of the block 43.

45 The lower jaw member of the yoke 51 is at its outer end upwardly inclined, as indicated at the numeral 54, which inclined face is rearwardly continued as at 55 substantially paralleling the face 56 of the upper jaw member 50. Intermediate these two parallel faces there is provided the vertical face 57 which is outwardly inclined as at 58, thus forming the inner wall of the jaw opening 49. The jaw faces just described are 50 arranged to conform to the hub structure 37 when the parts are in their normal position, as illustrated in Fig. 2 with the hub face 59 opposed to the jaw face 57, and the hub face 60 opposed to the jaw face 58. Thus the inner 55 end of the hub member 37 is provided with a plurality of faces angular to each other as, for instance, the faces 59 and 60, which are adapted upon the rotation of the lever 35 in a contra-clockwise direction to engage 60 against the jaw faces described and to move 65 the lever upon the engagement of its mutilated gear 52 with the rack 22 outwardly in reference to the jaws of the block 43 until, upon extreme movement, their positions will be substantially that illustrated in Fig. 3 of 70 the drawing. The brake rod 32, whose passage through the rear end of the yoke has been described, also extends through a perforation 61 longitudinally arranged in the block 43, and is provided at its end with a 75 member 62 which rests against a face 63 provided at the rear end of the vertical slot between the block arms 48. The perforation in the block member, as well as the aligned perforation 33 in the rear member of the 80 yoke are elongated in one direction as, for instance, horizontally to permit the passage of the similarly elongated T-head 62 upon the end of the brake rod 32, which brake rod in its assembly with the other parts is passed therethrough and then rotated 90° to its operative position, as shown by the dotted 85 lines 64 in Fig. 5 of the drawings.

90 The foregoing description of the parts of the device will make its operation readily understood. Assuming the parts to be in their normal position, as illustrated in Fig. 2 of the drawings, with slack in the brake rigging, it will be apparent that as the brake staff 12 is rotated, and thereby through the 95 chain 15 pull is exerted upon the free end of the lever 35, the entire assembly of parts—that is, the yoke 27, the block 43, the lever 35 and the spring 47 will move outwardly toward the end of the car—that 100 is, to the right in the drawing, pulling the brake rod 32 therewith and operating upon the equalizer bar and other parts not shown applying the brakes. Thus far in the operation the lever 35 will not rotate by reason, among other things, of the engagement of its hub within the jaws of the block and the gear 52 thereof will ride free of the rack 22. As this bodily movement of the parts 105 continues the slack is taken out of the entire rigging and tension is exerted upon the brake rod 32 and all of the brake shoes engaged against their wheels until the continued pull in the operation exerted through the operation of the brake staff, or other 110 suitable means, is transmitted through the pin 34 to the yoke 27, thus compressing the spring 47 between the yoke 27 and the block 43. During this operation the slack in the 115 rigging is taken up quickly and at a comparatively low average ratio. As the continued application of power overcomes the expanding pressure of the spring 47, the hub 37 will commence a withdrawal from the jaws of the block. When the spring 47 is fully 120 compressed and the stops 46 and 30 upon the block 43, and the yoke 27 respectively, are in engagement with each other continued pull upon the free end of the lever 35 will rotate said lever about the pin 34 125 130

until teeth 53 of the mutilated gear 52 upon said lever will engage with the rack 22. When so engaged, the lever 35 will walk upon the rack 22 and pull the yoke 27 and the block 43 within it further to the right or toward the brake rod. In effecting this change in the relation of the parts, the hub 37 upon the lever 35 is rotated out of the jaws of the block 43, and it will be understood that whatever the conformation of the hub in reference to the jaws, it must be a conformation that will permit of this rotation and of the relative outward movement of the lever in reference to the block 15 while the spring 47 is in full compression between its seats. When this position of the parts is assumed, as illustrated in Fig. 3 of the drawings, a very much increased leverage ratio is obtained to pull the rod, thereby enabling the operator of the brakes to apply, through this increased leverage, a great pressure of the brake shoes upon the wheels of the car. It will be obvious that, by means of this booster, a quick take-up of the slack 25 in the brake rigging parts may be effected, and that an automatic shift from the low leverage employed during take-up to a high leverage ratio will be immediately effected, permitting quick operation of the brakes 30 and application of a very high brake pressure upon the wheels of the car. On release of the brake chain the expanding of the spring will return the parts to their normal position.

25 Although I have herein shown and described what I now consider the preferred manner of carrying out the invention, the same is merely illustrative and I contemplate all changes and modifications that 40 come within the scope of the claims appended hereto.

I claim:—

1. In a brake rigging, the combination with a brake chain and a brake rod; of a 45 brake booster interposed therebetween said booster including a connecting lever between the rod and the chain and moving therewith when a comparatively low tension is upon the parts, and a fulcrum for said lever extraneous of the rod and chain against which the lever is adapted to engage, which lever rotates between the rod and chain upon a comparatively higher tension of the parts.
2. In a brake mechanism for railway cars, 55 the combination with the brake shoes and a power applying mechanism; of a connecting mechanism therebetween, the said connecting mechanism having interposed intermediate its ends a lever rotatable in respect 60 to the connecting mechanism; means for holding said lever against rotation under one tension of the connecting mechanism; means for permitting rotation under a higher tension of the mechanism; and a ful- 65 crum for said lever adapted to be engaged by it under said higher tension of the mechanism.
3. In a brake mechanism, the combination with brakes and power applying means; of a brake booster therebetween, said brake booster comprising a housing, a yoke slid- 70 able therein, means connecting said yoke to the brakes, a lever engaged to the power applying means and rotatably connected to the yoke; means associated with the yoke for holding the lever against rotation under one tension; and means for rotating said lever with reference to the yoke under a higher tension, the said means including co-engag- 75 ing means upon the housing and the lever. 80
4. In a brake mechanism, the combination of brake shoes and power applying means, and connections therebetween; of a brake booster mounted intermediate the ends of said connections, and including a lever and a block, said lever and block being interlocked upon a lower tension of the connecting link; a slid- 85 able connection between said lever and block; a fulcrum member for the lever disconnected with said lever under such tension and engaging the lever upon relative movement between the said lever and block. 90
5. In a brake mechanism, brake shoes, power applying means, a yoke connected to the brake shoes, a lever connected to the power applying means, a fulcrum member adapted to be engaged by the lever, a rotatable connection between the lever and the yoke, the lever being non-rotatable and mov- 100 ing with the yoke under a comparatively lower tension of the parts and engaging with the fulcrum and rotating in respect to the yoke under a higher tension of the parts. 105
6. In a brake rigging for a railroad car, in combination, a housing secured to the car, a yoke slid- 110 able therein, means adapted to connect said yoke to the brake shoes, a lever rotatably mounted on said yoke, means adapted to connect said lever to power applying means, the yoke being provided with means to hold the lever against rotation upon a lower tension of the parts, the housing being provided with a rack and the lever with a gear, the said gear being adapted to rotate with the lever into engagement with the rack upon a higher tension of the parts. 115
7. In a brake mechanism for railroad cars, the combination with brake shoes and power applying means; of a brake rod connected to the brake shoes; a lever connected to the power applying means; a yoke; a block slid- 120 ably mounted in said yoke, the said block being connected to the brake rod, the lever being rotatably connected to the yoke, the lever being in engagement with the block and slid- 125 able in reference thereto. 125
8. In a railroad car, in combination, a housing secured thereto, a yoke slidably mounted in said housing, a block slidably 130

mounted in the yoke, a spring interposed between the yoke and the block, a lever rotatably mounted upon the yoke, said lever having means to secure it to power applying mechanism, the block having a brake rod connected thereto, the housing being provided with a rack, the lever having gears thereon, the lever being rotatable into disengagement with the rack and then sliding with the block, the said lever upon compression of the spring being rotatable and then engaging with the rack.

9. In a railroad car, in combination, a housing secured to the car, a yoke slidably mounted therein, a block slidably mounted within the yoke, a lever rotatably connected to the yoke, the block being provided with means for connecting it to a brake rod, the lever being provided with means for connecting it to a power applying device, the housing having a rack, the lever being provided with a mutilated gear adapted to engage the said rack and also having a hub, the block having jaws adapted to receive said hub, the said lever being held against rotation by said block upon the application of a lesser power and then moving with said block in disengagement from the rack, and upon the application of a greater power the hub moving out of the jaws of said block and engaging the rack and said lever then engaging the rack.

10. In a railroad car, a housing associated therewith, a yoke within the housing, a block within the yoke, a lever rotatably connected to said yoke, the housing being provided with ways for the yoke, the block having a sliding connection with the yoke, the lever and housing being provided with inter-engaging means, the block and lever being also provided with inter-engaging means, the said lever when engaged to the block being disengaged from the rack, and when engaged to the rack being disengaged from its engaging means with the block.

11. In a brake mechanism, a brake booster comprising a housing, a yoke, a block, a lever and a spring, the housing having a rack and yoke ways, the yoke being received in said ways, the block being slidably connected to the yoke, the spring being mounted between the block and the yoke, the lever being pivotally connected to the yoke and having a gear for engaging it to the rack, the lever being also provided with a hub and the block having jaws to receive said hub, the lever being in disengagement from the rack when its hub is within the jaws of the block and engaging the rack when its hub is withdrawn from the jaws of the block.

12. In a brake mechanism, a brake booster comprising a housing, a yoke slidably mounted in said housing, a block slidably mounted in said yoke, a spring interposed

between the yoke and the block, a lever pivotally connected to said yoke, the block being bifurcated for the reception of the lever therein, the block having jaws and the lever having a hub adapted to enter said jaws, the housing having a rack and the lever having teeth adapted to engage the rack, the lever's hub being within the block's jaws when the spring is expanded, and upon compression of the spring engaging the rack and rotating its hub outside the said jaws.

13. In a brake mechanism, a brake booster comprising a housing, a yoke, a spring, a block, a lever and a pin, the housing being provided with a rack and with yoke ways and with key ways, the yoke being received in said yoke ways and adapted to slide therein, the block being provided with ways, and the yoke having beads entering said ways, the spring being mounted between the yoke and the block, the said yoke and block being each provided with stops to limit the compression of the spring, the pin passing through the yoke and the lever and entering at its ends the key way of the housing, the lever being provided with teeth to engage the rack of the housing, and also having a hub, the block being provided with a transverse opening to receive the hub, and a vertical slot to receive the lever, the said hub being within the transverse opening of the block when the lever's teeth are disengaged from the housing rack, and the hub being withdrawn therefrom when the lever's teeth are in engagement with the housing rack.

14. In a railroad car, a brake rigging having, in combination with a brake rod, a power applying means, a housing secured to the car, a yoke, a block, a lever, a spring and a pin, the housing having a top and side, its top being provided with a rack and its sides being provided with a yoke way and a pin way, the yoke being received within the yoke way, the block being slidably mounted within the yoke, the spring being interposed between the yoke and the block, the pin passing through the yoke and the lever and being received at its ends within the pin way of its housing, the block being provided with a vertical slot for the reception of the lever, the lever having a hub thereon and the block being provided with a transverse slot for the reception of said hub, the power applying means being connected to the said lever, the brake rod being connected to the block, whereby upon the application of the power applying means to the lever the lever and block move together while the spring is being compressed, and upon compression of the spring the hub of the lever is withdrawn from the block and rotates into engagement with the rack of the housing.

15. In a brake rigging for railroad cars, the combination with brake shoes; of a brake rod connected therewith; of power ap-

- plying means in the car, a housing secured to said car, a yoke slidably mounted in said housing, a block slidably mounted in said housing, a spring interposed between the said block and yoke and a lever, the lever being rotatably connected to the yoke, the housing and yoke having inter-engaging means, the block and lever having inter-engaging means, the power applying means being connected to the lever and during its initial movement compressing the spring while the lever and the block are engaged, and upon its further movement, rotating the lever into disengagement from the block and engaging it with the housing. 15
16. In a brake rigging, in combination, a brake rod, a block connected thereto, a lever, a yoke connected thereto, a housing, a spring, and a power applying means, the latter being connected to the lever, the housing supporting the yoke, the spring being interposed between the yoke and the block, the spring holding the block in engagement with the lever, the yoke withdrawing the lever from the block when the power applied compresses the spring to a predetermined point. 25
17. In a brake rigging, in combination, a brake rod, a lever, a pair of spring pressed members connecting the lever and the brake rod; power applying means connected to the lever, and the lever entering into locking engagement with one of said members when the spring is expanded, and unlocking therefrom and rotating in respect to the other member when the spring is compressed. 35
18. In a brake rigging for cars, in combination, a car body, a brake rod, a lever fulcruming upon the car body; power applying means connected to the lever; a spring connection between the brake rod and the lever, a lever locking member associated with the spring, said member holding the lever disengaged from its fulcrum until the power applying means effects a predetermined compression of the spring. 45
19. In a brake rigging, cars having a brake rod and power applying means, a lever connected to the power applying means, a spring connection between said lever and the brake rod, limiting stops for said spring, means holding said lever inoperable as a lever until the stops limit the compression of the springs. 50
20. In a brake booster, having a brake rod, power applying means and a power multiplying lever interposed therebetween, the combination therewith of a locking block for said lever, the said locking block having means holding the lever inactive as a lever until a predetermined power is applied through the power applying means. 60
21. In a brake rigging for railroad cars, in combination, a car body, a housing secured thereto, a yoke slidable therein, a block
- slidable in reference to the yoke, a brake rod connected to the block, power applying means, a lever connected thereto and associated with the yoke, the yoke and block being perforated, the brake rod passing through said perforations and having a head engaging it to the block. 70
22. In a brake rigging, a sliding yoke, a housing therefor, a brake rod, a slidable block associated with the yoke and connected to the brake rod, a spring between said block and the yoke, a lever rotatably connected to the yoke, means locking the lever to the block in normal position of the spring, the lever disengaging from its locked position, fulcruming on the housing and rotating in reference to the yoke on compression of the spring. 75
23. In a railroad car, the combination with the car body of a housing secured thereto, a yoke, a block, a pin, a spring, a rod, and power applying means, the housing being provided with means for supporting the yoke, and having a rack and key ways, the block being slidably supported by the yoke, and having a jaw and a lever slot, the pin passing through the yoke and entering the key ways of the housing, the spring being interposed between the block and the yoke, the brake rod being connected to the block, the power applying means being connected to the lever, the lever having a hub entering the jaws of the block and resting within the slot of the block in normal position, the lever being also provided with teeth, the yoke upon pull of the power applying means moving forwardly and the block moving therein in the same direction and at a slower rate while the spring is being compressed, the hub of the lever withdrawing from the jaw of the block on a determinate compression of the spring, the lever thereupon rotating on the pin and engaging its teeth upon the rack of the casing. 95
24. In a railroad car, the combination with a brake equalizer, power applying means and a lever; of a stationary housing secured to the car, a yoke slidable therein, a member slidable in reference to the yoke, means connecting said member to the brake equalizer, means connecting the lever to the power applying means, the lever sliding with the yoke on the application of certain power and being rotatable in reference to the yoke and having a fulcrum engagement with the housing on the application of greater power. 105
25. In a brake booster, in combination, a housing, a slidable yoke and a slidable block associated therewith, a spring interposed between the yoke and block, a lever engaging the block and sliding therewith, a brake rod connected to the block, power applying means connected to the lever, the lever locking with the block in a lesser separating 120
- 125
- 130

- pull between it and the block, and disengaging therefrom and having a fulcrum engagement with the housing on a greater separating pull between the block and lever.
26. In a brake mechanism, the combination with power applying means; of connecting means between said power applying means and the brake shoes, said second named means including a pull-link and a power multiplying lever connected therewith for movement angularly relatively thereto to multiply the power, interengaging means on said lever and link operating to prevent angular movement thereof and adapted to be come disengaged when a predetermined resistance is offered to the movement of said link thereby, permitting angular movement of the lever and effecting multiplication of the applied power.
27. In a hand brake, the combination with power applying means; of means operatively connecting said power applying means with the brake mechanism proper, including a power multiplying lever and a device for limiting the lever to movement of translation during a predetermined portion of the brake tightening operation, said device being rendered inoperative upon engagement of the brake shoes with the wheels whereby said lever is permitted to swing and multiply the power.
28. In a hand brake, the combination with a pulling mechanism; of a power multiplying mechanism connected therewith, said last named mechanism including a lever
- through which the entire pulling force is transmitted, a link pivotally connected to the lever and to the brake mechanism proper, and means for locking said lever against pivotal movement relative to said link, said means being adapted to yield and release said lever when the parts are subjected to a predetermined tension.
29. In a hand brake, the combination with means for exerting a pull; of a power multiplying mechanism operatively connected to said means, said mechanism including a lever having swinging movement and movement of translation; and means for preventing swinging movement of said lever, said means being rendered inoperative when the parts are subjected to a predetermined tension to permit swinging movement of the lever and effect multiplication of the applied power.
30. In a brake rigging, a pulling mechanism, said mechanism including a pivoted and bodily movable lever mechanism, means for rendering said lever mechanism in-operative under a relatively low power pull, and automatically rendering said lever mechanism operative under a high power pull.
- In witness that I claim the foregoing I have hereunto subscribed my name this 18th day of August, 1922.

HARLEY E. ANDERSON.
